UNITED STATES PATENT OFFICE.

JOHANN C. SELL, OF PRYOR, OKLAHOMA.

LOADING MECHANISM.

Application filed December 4, 1920. Serial No. 428,298.

To all whom it may concern:

Be it known that I, JOHANN C. SELL, a citizen of the United States, residing at Pryor, in the county of Mayes and State of Oklahoma, have invented certain new and useful Improvements in Loading Mechanisms, of which the following is a specification, reference being had to the accompanying drawings.

10 This invention relates to certain improvements in loading mechanisms and has relation more particularly to a device of this general character especially designed and adapted for use in connection with shocks, 15 and it is an object of the invention to provide a device of this general character embodying a sweep supported for vertical swinging movement, together with novel and improved means for imparting upward 20 movement to the sweep.

Another object of the invention is to provide a device of this general character of a portable type including a sweep, together with means whereby the load received by the 25 sweep may be readily and conveniently delivered to a collecting or receiving member such as a trailing barge.

An additional object of the invention is to provide a novel and improved device of 30 this general character including a sweep supported for swinging movement in a vertical direction, together with power driven means for imparting upward movement to the sweep and wherein means are employed 35 to assure the downward movement of the sweep after discharging its load.

Furthermore, it is an object of the invention to provide a device of this general character embodying a vertically movable 40 sweep, together with novel and improved means whereby the downward movement of the sweep may be readily regulated in accordance with the requirements of practice.

The invention consists in the details of 45 construction and in the combination and arrangement of the several parts of my improved loading mechanism whereby certain important advantages are attained and the device rendered simpler, less expensive and 50 otherwise more convenient and advantageous for use, as will be hereinafter more fully set forth.

The novel features of my invention will hereinafter be definitely claimed.

55 In order that my invention may be the

better understood, I will now proceed to describe the same with reference to the accompanying drawings, wherein:

Figure 1 is a view partly in side elevation and partly in section illustrating a loading mechanism constructed in accordance with an embodiment of my invention, a second position of the sweep being indicated by dotted lines. 60

Figure 2 is a view partly in section and 65 partly in top plan of the structure as disclosed in Figure 1.

Figure 3 is a view in rear elevation of certain of the parts comprised in my device as herein set forth, and 70

Figure 4 is a fragmentary view illustrating in detail the braking mechanism herein employed.

As disclosed in the accompanying drawings, T denotes a portable body and preferably a tractor and which includes a casing 1 for the shafts of the rear or drive wheels D. Engaged with the opposite end portions of the casing 1 are the rear end portions of the elongated arms 2 having swinging movement 75 in a vertical direction. The arms 2 are arranged inwardly of the wheels D and extend forwardly of the body or tractor T inwardly of the front or steering wheels F and terminate in advance of the body or tractor 80 when said arms 2 are substantially horizontal or in their lowermost position.

Carried by the forward end portions of the arms 2 and in advance of the portable body or tractor T is a sweep S of a conventional type adapted to be employed in connection with shocks or the like. 90

Extending rearwardly from the opposite end portions of the casing 1 and inwardly of the arms 2 are the rearwardly directed 95 beams 3 immovable with respect to the body or tractor T and which preferably terminate rearwardly of the wheels D. The rear end portions of the beams 3 support the uprights 4 disposed on a slight forward incline. Connecting the upper portions of the uprights 4 and the forward portion of the body or tractor T are the brace members 5 whereby said uprights are maintained in a rigid position. 100

A transversely disposed shaft 6 is rotatably supported by the rear end portions of the beams 3 and the lower portions of the uprights 4 and said shaft at a point substantially midway between the uprights 4 110

is provided with an annular flange 7 so that the portion of the shaft 6 between the uprights 4 constitutes a pair of separated winding drums.

5 Fixed to one end portion of the shaft 6 is a relatively large pulley 8 around which is disposed a belt 9. The belt 9 extends forwardly of the body or tractor T and is also disposed around a pulley 10 in driven connection with the engine of the tractor or with any other suitable source of power carried by the body T. The upper stretch of the belt 9 passes under an idle pulley 11 rotatably supported by the body or tractor T 15 rearwardly of but in close proximity to the driven pulley 10 to assure, under certain conditions, the proper gripping action of the belt 9 upon said pulley 10.

The upper stretch of the belt 9 also passes 20 under an idle pulley 12 rotatably supported by the free end portion of an elongated arm or lever 14 having its opposite end portion loosely engaged with the shaft 6 so that said arm may be capable of vertical swinging 25 movement.

The arm or lever 14 has rigidly connected therewith an upstanding and forwardly inclined lever 15. This lever 15 provides means whereby downward pressure may be 30 imposed upon the arm 14 to cause the pulley 12 to tighten the belt 9 so that said belt will have requisite frictional or gripping engagement with the pulley 8 so that the shaft 6 may be rotated in one direction at the will 35 of the operator.

Rotatably supported by the upper end portions of each of the uprights 4 are the pulleys 16 over which pass the flexible members 17. The forward end portions of the 40 members 17 are secured to the rear portions of the sweep S adjacent the opposite ends thereof while the opposite end portions of said members are secured to the opposite end portions of the shaft 6 and are adapted to 45 be wound therearound upon rotation of said shaft 6 through the instrumentality of the belt 9. This winding of the members 17 upon the shaft 6 results in an upward swinging movement of the sweep S so that 50 the load thereon may be delivered or discharged rearwardly of the body or tractor T and preferably within a trailing barge or wagon fragmentarily indicated by B. The upper end portions of the uprights 4 are 55 connected by a downwardly and rearwardly inclined apron 18 upon which the load from the sweep is initially received and which serves to assure the proper delivery of the load within the barge B.

60 Just before the sweep S reaches the limit of its upward movement, the arms 2 come into contact with the transversely disposed rod or member 19. This member 19 is secured at its opposite end portions to the bolts 20 slidably disposed through the upper

portions of the uprights 4 and movable in a direction longitudinally of the body or tractor T. These bolts 20 extend in advance of the uprights 4 and terminate in the enlargements 21.

70 Interposed between the enlargements 21 and the forward edges of the uprights 4 are the expandable members 22 herein disclosed as coil springs encircling the forward end portions of the bolts 20. As the arms 2 75 come in contact with the rod 19, the same impose sufficient endwise movement to the bolts 20 to place the expandable members or springs 22 under tension so that when the operator swings the arm 12 upwardly to 80 render the belt 9 inoperative, the springs 22 will automatically impose return movement to the sweep S, the tension of said springs being sufficient to throw the arms 2 beyond a vertical center.

85 As the sweep S descends and the flexible members 17 unwind, the shaft 6 will be rotated in a direction reverse to its rotation by the belt 9. It is of importance to regulate or brake this second rotation of the 90 shaft 6 to control the downward movement of the sweep S. As herein disclosed, the shaft 6 has fixed thereto a disc or brake wheel 23 with which coacts a brake strap 24, said strap being operated in a well 95 known manner through the medium of the lever 25. By proper operation of the lever 25, the sweep S may be brought to a stop at any point during its downward movement or such movement may be at a speed preferred and particularly at such speed to cause the sweep S to reach its lowered position or come in contact with the ground without undue force or impact.

100 The lever 25 is provided with a conventional type of latch mechanism 26 coacting with the rack 27 so that the lever 25 may be locked in its desired position either to lock the sweep S in an elevated position to hold the strap 24 in such contact with the coacting disc or brake wheel to maintain the lowering movement of the sweep S at a pre-determined rate of speed.

105 It is to be understood in practice that the body or tractor T is caused to travel forwardly with the sweep S in its lowered position to properly engage the shock or other load to be elevated.

110 From the foregoing description it is thought to be obvious that a loading mechanism constructed in accordance with my invention is particularly well adapted for use by reason of the convenience and facility with which it may be assembled and operated, and it will also be obvious that my 115 invention is susceptible of some change and modification without departing from the principles and spirit thereof and for this reason I do not wish to be understood as limiting myself to the precise arrangement 120

and formation of the several parts herein shown in carrying out my invention in practice except as hereinafter claimed.

I claim:

- 5 1. A loading device of the class described comprising a portable body, uprights carried thereby, arms supported by the body for swinging movement in a vertical direction, said arms being of a length to extend in advance of the portable body when substantially at their lowermost position, a sweep carried by the forward end portions of the body, a rotatable member, a flexible member coacting with the rotatable member and the sweep, the upper portion of the uprights being provided with guiding means over which said flexible connection passes, so that the sweep is swung upwardly upon rotation of the rotating member in one direction, means operable at will for imparting the desired rotation to the rotatable member to swing the sweep upwardly, said sweep moving downwardly by gravity, members slidably disposed through the uprights, a rod connecting the uprights and with which the arms engage during the upward swinging movement of the sweep, means placed under tension by such contact of the arms with the rod for automatically imparting initial downward movement to the sweep, and means coacting with the rotatable member for braking the downward movement of the sweep. 40
- 10 15 20 25 30 35 45 50 55 60 65 70 75 2. A loading device of the class described comprising a portable body, uprights carried thereby, arms supported by the body for swinging movement in a vertical direction, said arms being of a length to extend in advance of the portable body when substantially at their lowermost position, a sweep carried by the forward end portions of the body, a rotatable member, a flexible member coacting with the rotatable member and the sweep, the upper portion of the uprights being provided with guiding means over which said flexible connection passes, so that the sweep is swung upwardly upon rotation of the rotating member in one direction, means operable at will for imparting the desired rotation to the rotatable member to swing the sweep upwardly, said sweep moving downwardly by gravity, members slidably disposed through the uprights, a rod connecting the uprights and with which the arms engage during the upward swinging movement of the sweep, means placed under tension by such contact of the arms with the rod for automatically imparting initial downward movement to the sweep, and means coacting with the rotatable member for braking the downward movement of the sweep. 40
- 15 20 25 30 35 40 45 50 55 60 65 70 75 3. A loading device of the class described comprising a body, an upright carried by the body, members slidably disposed through the body, a sweep carried by the body and supported for movement in a vertical direction, means for swinging the sweep upwardly, said sweep moving by gravity in the opposite direction, means associated with the members and engaged by the sweep for imparting movement to said members in one direction, and means coacting with said members and placed under tension by such engagement of the sweep to automatically impart initial movement to the sweep in a downward direction. 40

In testimony whereof I hereunto affix my signature.

JOHANN C. SELL.
